(57) **CLAIM**

We claim the ornamental design for a spool handle, as shown.

DESCRIPTION

FIG. 1 is a front elevation view of our new design for a spool handle.

FIG. 2 is a perspective view of our new design for a spool handle.

FIG. 3 is a side elevation of our new design for a spool handle; and,

FIG. 4 is another perspective view of our new design for a spool handle with dashed lines showing it in context with a spool.

The broken line showing of a spool is included for the purpose of illustrating environmental structure and forms no part of the claimed design.
